UNITED STATES PATENT OFFICE.

HENRY GAZAILLE AND HAMILTON F. LOW, OF MANCHESTER, NEW HAMPSHIRE; SAID LOW ASSIGNOR TO SAID GAZAILLE.

AIR-PUMP.

SPECIFICATION forming part of Letters Patent No. 349,428, dated September 21, 1886.

Application filed December 30, 1885. Serial No. 187,141. (No model.)

To all whom it may concern:

Be it known that we, HENRY GAZAILLE, a subject of the Queen of Great Britain, and HAMILTON F. Low, a citizen of the United States, both residing at Manchester, in the county of Hillsborough and State of New Hampshire, have invented certain new and useful Improvements in Air-Pumps, of which the following is a specification.

10 Our invention relates to air-pumps combining in their operation the action of force and suction.

The object of our invention is to construct an air-pump which shall, by the action 15 of certain improved valves connected therewith, be capable of forcing air into a tube or receiver by the movement of the piston in one direction, and exhausting the air from said tube or receiver by the opposite movement of 20 said piston.

Our invention consists in details of construction described below, and pointed out in the claims.

In the accompanying drawings, forming part 25 of this specification, Figure 1 represents a sectional side elevation of our improved air-pump; Fig. 2 being an end view of the same. Fig. 3 is a detailed side elevation of the valve-housing, showing a section of the piston-rod and valve-rod in position. Fig. 4 is a detailed 30 plan view of the valve-housing alone. Fig. 5 is a transverse section of Fig. 3, taken between the valve-seats and the side openings, and having valves and the valve-rod removed. The barrel of the pump is composed of an interior and exterior cylinder. The interior cylinder, A, in which the piston moves, is formed of some 35 suitable sheet metal or zinc, while the exterior cylinder, A', is composed of some tough material, such as sheet iron. This latter cylinder is provided simply to prevent the interior cylinder from becoming dented or otherwise marred; but one end of the pump-barrel is closed, the head B having a base, b, by which 40 it may be secured to the floor serving this purpose. The other end is provided with simply a ring, B', its outer diameter being equal to that of the head B, and having a base, b', by which it may be fastened down. The opening 45 b' in this ring B' may be nearly or quite the

diameter of the interior cylinder, A, a convenient means of uniting the parts A A' B B' being shown in the drawings, in which the end of the exterior cylinder, A', enter grooves formed annularly in the head B and ring B', 55 the ends of the cylinder A, bearing against shoulders formed for the purpose on the said parts B B', and all said parts being held firmly together by the bolts C passing through the head B between the cylinders A A', and through the ring B', to the projecting ends of which are threaded-nuts c, as in Figs. 1 and 2. To the interior cylinder is fitted a piston, D, preferably formed of wood, and, as it is a very difficult matter to bend up the zinc or other metal 65 forming said cylinder so that it may be even moderately true and impossible to form it perfectly cylindrical, it becomes necessary to provide a very flexible packing for the said piston.

After numerous experiments we find that 70 flexible rubber tubing E, placed in an annular groove formed in the piston D, is decidedly the best material for the purpose, and forms a perfectly flexible packing, which readily overcomes all irregularities of the cylinder A. 75

To overcome any possible adhesiveness or unnecessary wear of the rubber tubing E, it may be covered by a strip of silesia or other coarse linen cloth, and its sides tucked into the groove on either side of the tubing. A 80 rectangular piston-rod, F, enters one end of the valve-housing G, in which it may be properly secured by a bolt or rivet, f. At the opposite end of said valve-housing is formed a circular flange, g, by which it is secured by screws to the 85 piston D. It may be here noted that said piston has a central opening, d, connecting with the interior of the valve housing, for the passage of air. Valves H H' are hinged at their top within said housing G, so as to fall against seats 90 g' g', each of said valves being adapted to move away from the other when opening and toward the other when closing. These valves are operated automatically with the outward and return stroke of the piston-rod F, as follows: A rocker-arm, I, having its lower end mounted upon a shaft, J, which may pass through one or both side walls of the housing G, midway from either of the valve-seats g' g', is adapted to bear against either of the valves 95 100

alternately by means of a crank, K, mounted upon the shaft J, outside of said housing, to the free end of which is attached a rod, L, mounted in a suitable bearing, m, formed upon 5 one side of the stand M, supporting the piston-rod F, and provided either side of said bearing m, with a collar, as in Fig. 1, these collars l l' being so placed relative to said bearing m as to alternately strike the same just 10 before the piston-rod shall have completed its stroke in either direction, thereby holding said rod L sufficiently long to reverse the valves by the action of the crank K and rocker-arm I.

To insure the perfect operation of the rod 15 L and its collars l l', said rod and the piston-rod F must move together or simultaneously, except when either of the collars strike the bearing m, as previously explained. In order to do this, a boss, g², is formed upon one of the 20 side walls of the valve-housing G, and so located as that the crank K must slide past it when completing its stroke in either direction, and by means of the spiral spring j on shaft J, which spends its force between the valve-housing 25 and the rocker-arm I, said crank K will readily snap to either side of said boss, and so remain until either of the collars l l', acting upon the bearing m, shall reverse it.

The piston-rod may be operated in various 30 ways, one of which is illustrated in Fig. 1. A suitable hand-lever, N, is fulcrumed at n to the stand M, and arranged to operate the piston-rod F by means of a connecting-rod, O.

The most convenient place for connecting 35 the pump with a tube or receiver will probably be through the head B, as at b³, in which the end of a tube, P, is inserted.

When using this pump for inducing an air-current through a pneumatic dispatch or parcel tube, the improved valve mechanism herein described will prove of great advantage, for the reason that by its use the said dispatch-tube is not necessarily limited in length. If one stroke of the piston is not enough to accomplish the desired result, it may be given 45 several strokes, each of which will carry the article farther along in the tube—i. e., when the valves are in the position shown in Fig. 1, by drawing out the piston-rod the air in the 50 tube P will be withdrawn or exhausted, and thus carry anything contained therein toward the pump. If, after the piston has nearly reached the open end of the pump, it is found that the article in said tube P has not reached 55 its destination, the piston must be reversed by means of the hand-lever N, and before the collar l has reached the bearing m, so that the position of the valves may remain unchanged. By this means the valve H' will open automatically by the pressure of air and allow 60

enough air to escape to permit the piston to again occupy the position shown in Fig. 1 without having forced any more air into the tube. After repeating this as required to draw anything through the tube P to its destination, 65 the lever N may then be moved far enough to cause the collar l to strike the bearing m, which will reverse and set the valves for forcing air into the tube.

Having described the construction of our 70 improved pump, what we claim, and desire to secure by Letters Patent, is—

1. The combination, with the cylinder, of the piston and its rod, the valve-housing arranged between the two, the valves within the 75 housing, a rocker-arm between the valves, a wrist connecting said arm with a crank and stop-rod outside of the housing, and a suitable bearing for the stop-rod, whereby the piston and stop-rod move together, or the valves may 80 be reversed just before the end of the piston-stroke, as set forth.

2. The combination, with the valve-housing placed between the piston and its rod, and provided with an external boss, of the internal 85 valves, the rocker-arm between them, the wrist, the spring between the rocker-arm and the crank, the said crank, and the rod provided with the stop-collars and a suitable bearing, as set forth.

3. The combination, with the cylinder, composed of the inner sheet-metal portion, A, and the outer portion, A', of tougher metal, of the tube P in the cylinder-head, the piston D, having ring-packing E and air-port d in front 95 of the valves, the valve-housing G between the piston and its rod, the valves H H' within the housing, the valve rocker-arm I, the wrist J, the spring j between the rocker I and crank K, the said crank, and the boss g² on the outer 100 side of the housing for engaging with the former, the rod L, operating the crank, and provided with collars l l', the standard M, having upper bearing, m, supporting said rod and acting as a stop for its collars, the lever N, pivoted 105 to the standard, the link O, and the piston-rod F, as set forth.

4. In an air-pump, the combination, with the sheet-metal cylinder A, of the piston provided with an annular groove containing a 110 tubular rubber packing covered with silesia or the equivalent, as and for the purpose set forth.

In testimony whereof we affix our signatures in presence of two witnesses.
